UNITED STATES PATENT OFFICE.

RALPH A. MCKINNEY, OF PITTSBURGH, PENNSYLVANIA.

DESIGN FOR A CABINET FOR WIRELESS RECEIVING APPARATUS.

Application filed July 29, 1922. Serial No. 3,246. Term of patent 7 years.

To all whom it may concern:

Be it known that I, RALPH A. MCKINNEY, a citizen of the United States, residing at Pittsburgh, in the county of Allegheny and State of Pennsylvania, have invented a new, original, and ornamental Design for Cabinets for Wireless Receiving Apparatus, of which the following is a specification, reference being had to the accompanying drawings, forming part thereof.

Fig. 1 is a front elevation of the cabinet.

Fig. 2 is a perspective view of the cabinet.

I claim:

The ornamental design for a cabinet for wireless receiving apparatus, as shown.

In testimony whereof I affix my signature.

RALPH A. MCKINNEY.
